US0D1023215S

(12) **United States Design Patent** (10) **Patent No.:** **US D1,023,215 S**
(45) **Date of Patent:** **** Apr. 16, 2024**

(54) **MAGAZINE FOR FIREARM**

(71) Applicant: **22 Evolution LLC**, Boonville, MO (US)

(72) Inventors: **John L. Overstreet**, Fayette, MO (US); **Jordan Maddox Wilson**, Blue Springs, MO (US); **Derrik Lee Roll**, Columbia, MO (US)

(73) Assignee: **22 Evolution LLC**, Boonville, MO (US)

(**) Term: **15 Years**

(21) Appl. No.: **29/881,682**

(22) Filed: **Jan. 5, 2023**

Related U.S. Application Data

(62) Division of application No. 29/782,546, filed on May 7, 2021, now Pat. No. Des. 987,763.
